UNITED STATES PATENT OFFICE.

CHARLES A. UPSON, OF LOCKPORT, NEW YORK.

FASTENING DEVICE FOR WALL-BOARD, &c.

1,297,611.

Specification of Letters Patent. Patented Mar. 18, 1919.

Application filed December 16, 1918. Serial No. 266,847.

To all whom it may concern:

Be it known that I, CHARLES A. UPSON, a citizen of the United States, residing at Lockport, in the State of New York, have 5 invented certain new and useful Improvements in Fastening Devices for Wall-Board, &c., of which the following is a specification, reference being had to the accompanying drawing, forming a part hereof.

This invention has for its object to provide an improved blind fastener for use in securing wallboard in place in such a manner as to avoid nailing through the fasteners within their edges and thus to avoid disfiguring the exposed surface of the board. As will be apparent, the improved fastener is applicable to other specific uses of a similar character in which a blind fastener is desirable. The specific purposes in view in 10 the present case are to facilitate the securing of the fastener to the studding or other part to which the wall board is to be secured, to assure the firm and permanent engagement between the fastener and the wallboard, and 15 to prevent the tendency of the wallboard to slip to one side or the other as it is being applied. The invention will be more fully explained hereinafter with reference to the accompanying drawing in which it is illustrated, and in which—

Figure 1 is a view in front elevation, showing the improved fastener in place against the studding.

Fig. 2 is a view of the same as seen from 35 the left hand in Fig. 1.

Fig. 3 is a view of the same as seen from above, the position of the wallboard, as it is being applied, being also shown.

Fig. 4 is a view similar to Fig. 3, but 40 showing the wallboard driven home upon the fastener.

The improved fastener consists of a thin, flat, metal plate *a* of any desired form, it being shown in the drawing as rectangular. 45 It has, extending from one edge inward, a nailing slot *b*. It has also, preferably struck up because of economy in manufacture, two prongs *c* which are slightly bent away from the central plane, so that when the 50 wallboard is forced against them, as by pounding, they will enter the wallboard and will be spread laterally, all as shown clearly in Figs. 3 and 4. In order that any tendency of the board to draw away from the 55 prongs may be overcome, they are so formed, as by being provided with teeth or barbs

c', that they will become firmly anchored in the wall board, the material of which will close around the toothed or barbed prongs and engage the same. In the practical use of blind fasteners of this character, it has been found that in applying the wallboard it will sometimes slip to one side, one of the prongs *c* remaining substantially straight while the other is bent more. 60 To overcome this tendency the fastener is provided with a perpendicular prong *d*, which may also be toothed or barbed or otherwise formed to engage the wallboard, as shown at *d'*. This perpendicular prong 70 enters the wallboard as soon as it has been started upon the bent prongs *c* and then prevents any lateral slipping of the wallboard.

In the use of the improved fastener the nail *e* is first driven into the studding *f*, but 75 is not driven home. The fastener *a* is then slipped upon the nail, by means of the slot *b*, this operation being much more easily effected in this manner than would be possible if the hole for the nail did not extend 80 to the edge, which would require both the fastener and the nail to be held while the nail is struck by the hammer. When the fastener has been secured in position by driving the nail home, the wallboard is 85 placed against the ends of the prongs *c* and is forced home, as by blows of a hammer or mallet against a piece of board laid against the front surface of the wallboard. In this operation the prongs *c*, which are already 90 bent apart somewhat, are caused to bend farther apart, as shown in Fig. 4, and at the same time the perpendicular prong *d* is made to enter the wallboard so as to prevent lateral slip.

95 I claim as my invention:

1. A blind fastener for wallboard, etc., to be placed between the wallboard and the studding to which the wallboard is to be fastened, consisting of a thin, flat, metal 100 plate having a slot opening from one edge to receive a fastening means to secure the plate to a studding and provided on the side toward the wallboard with struck-up prongs having pointed ends and so bent that they 105 will enter the wallboard and spread laterally to engage and retain it when the wallboard is forced against the fastener.

2. A blind fastener for wallboard, etc., to be placed between the wallboard and the 110 studding to which the wallboard is to be fastened, consisting of a thin, flat, metal

plate having an opening therein to receive a fastening means to secure the plate to a studding and provided on the side toward the wallboard with struck-up prongs having pointed ends and so bent that they will enter the wallboard and spread laterally to engage and retain it when the wallboard is forced against the fastener, the prongs being formed to become anchored in the wallboard.

3. A blind fastener for wallboard, etc., to be placed between the wallboard and the studding to which the wallboard is to be fastened, consisting of a thin, flat, metal

plate having an opening therein to receive a fastening means to secure the plate to a studding and provided on the side toward the wallboard with struck-up prongs having pointed ends and so bent that they will enter the wallboard and spread laterally to engage and retain it when the wallboard is forced against the fastener, the plate also having a perpendicular prong to enter the wallboard and prevent lateral slip of the same.

This specification signed this 10th day of December, A. D. 1918.

CHARLES A. UPSON.
